UNITED STATES PATENT OFFICE.

CHARLES E. WHITTLESEY, OF NEW HAVEN, CONNECTICUT, ASSIGNOR OF ONE-HALF OF HIS RIGHT TO JOSEPH L. JOYCE, OF SAME PLACE.

DEVICE FOR REPAIRING HEEL-LININGS OF BOOTS AND SHOES.

SPECIFICATION forming part of Letters Patent No. 228,709, dated June 8, 1880.

Application filed March 27, 1880. (Model.)

To all whom it may concern:

Be it known that I, CHARLES E. WHITTLESEY, of New Haven, in the county of New Haven and State of Connecticut, have invented 5 a new Device for Repairing Heel-Linings of Boots and Shoes; and I do hereby declare the following, when taken in connection with the accompanying drawings and the letters of reference marked thereon, to be a full, clear, 10 and exact description of the same, and which said drawings constitute part of this specification, and represent, in—

Figure 1, a perspective view of the stay as prepared for insertion; Fig. 2, longitudinal 15 section of the heel portion of a shoe with the stay applied; Fig. 3, the stay as cut flat; Fig. 4, the same as shaped for insertion.

This invention relates to an improvement 20 specially designed for the repair of boots and shoes.

In that class of boots and shoes which are lined at the heel the lining soon wears through and frequently becomes a source of great annoyance to the wearer, and if repair is attempted it generally adds to the discomfort 25 of the wearer.

The object of this invention is the construction of a flexible stay which may be readily and easily applied to the shoe and avoid the 30 before-mentioned inconvenience; and it consists in the construction as hereinafter described, and particularly recited in the claim.

From leather fabric or other suitable flexible material a gore-shaped piece, A, (see Fig. 3,) is cut, and at its lower or broader end a notch, B, is cut, leaving the two edges *a b* at nearly a right angle to each other. These two edges *a b* are then brought together, as seen in Fig. 4, which gives a transverse curvature 40 to the upper portion and brings the two edges *a b* at nearly right angles to the upper portion, and corresponding nearly to the shape of the heel of the foot. Then over the joint-edges *a b* a short thin heel-piece, C, is placed, 45 and secured by stitching or otherwise. This completes the stay. It is then placed in the shoe to be repaired at the heel, the heel-piece

C beneath the insole D, the part A extending up over the worn or broken lining, as seen in Fig. 2, where it may be secured by simply over-stitching the edge onto the lining; or it may be stitched to the shoe through and through. This covers the worn portion of the lining, 50 forms a new surface for the heel, and practically makes the lining equally as good as in 55 its original condition.

The stay may be composed of the single piece A, without the heel-piece C, by simply uniting the edges *a b*, that part forming the bearing for the heel, but it must be of a flexible material, because it is to be introduced 60 after the shoe is worn; and if rigid and in the nature of a stiffener it could not be so applied, and would not accomplish the object.

The insole D is not essential, as the heel of 65 the foot may rest directly on the heel portion of the stay.

The stay thus produced becomes an article of manufacture, and is of such character that an unskilled person may easily attach it to 70 the shoe.

I do not broadly claim an additional or inner lining for a boot or shoe, as such, I am aware, has been introduced in the process of manufacture; nor do I claim a counter support or stiffener which is practically rigid; 75 but I am not aware that a heel-stay has been produced as an article for the repair of the lining of shoes, and which is the essential feature and object of this invention.

I therefore claim—

As a new article of manufacture, the inside heel-stay for the repair of lining of boots and shoes, constructed of leather or other suitable flexible material, as described, having the upper flexible curved portion, A, and the heel-piece C, and adapted to be secured to the inside of a worn boot or shoe, substantially as specified.

CHARLES E. WHITTLESEY.
